UNITED STATES PATENT OFFICE

115,113

DESIGN FOR A SUPPORTING BAR RACK

Ota O. Hobson, Chariton, Iowa

Application July 18, 1938, Serial No. 78,568

Term of patent 3½ years

To all whom it may concern:

Be it known that I, Ota O. Hobson, a citizen of the United States, resident of Chariton, Lucas County, Iowa, have invented a new, original, and ornamental Design for a Supporting Bar Rack, of which the following is a specification, reference being had to the accompanying drawing, forming a part thereof.

Fig. 1 is a front elevational view of the article showing my design, and Fig. 2 is a top plan view of the same.

I claim:
The ornamental design for a supporting bar rack, substantially as shown.

OTA O. HOBSON.
